APPARATUS FOR HEAT TREATING METAL BODIES

Homer W. Jones, Westfield, N. J., assignor to The Linde Air Products Company, a corporation of Ohio

Application August 11, 1939, Serial No. 289,558

9 Claims.

(CL. 266—4)

This invention relates to apparatus for the heat treatment of metal bodies having a plurality of integral portions of the same longitudinal extent, and more particularly to the heat treatment of cams upon a camshaft. This invention also relates to apparatus for hardening the surface of a plurality of cams upon a camshaft in which the surfaces to be hardened are heated by sources of localized high temperature heat, such as oxy-acetylene blowpipe flames.

Heretofore, camshafts have generally been made of mild chrome-nickel or straight carbon steel forgings, and the wearing surfaces have been hardened by carburizing to retard wear. This hardening process has been found to be costly not only for the reason that the entire camshaft is copper plated and the wearing surfaces to be hardened are machined, but also for the reason that after the exposed surfaces are carburized they must be heat treated, and this heat treatment necessitates heating and quenching the entire camshaft. Furthermore, straightening camshafts after the above treatment adds considerably to the cost of the process.

By utilizing sources of localized high temperature heat, and heating only those portions desired to be hardened, thermal stresses in the body of the camshaft may be avoided; a straight carbon steel, such as S. A. E. 1045, may be used; and a single treatment may be utilized to harden the cams. This will effect a considerable reduction in costs, since the copper plating, machining, carburizing, and straightening steps of the previous method are eliminated.

Due to the extreme diversity of physical dimensions of camshafts and cams, such as overall length, distance between cams, cam width, cam ramp contours, etc., apparatus for hardening cams on a cam shaft, to be successful, must necessarily possess sufficient flexibility so that the least possible time will be required to align the blowpipe heads with respect to the work, or to make adjustments for cam spacing and other variables.

The objects of this invention are to provide apparatus for heat treating a plurality of portions of the same longitudinal extent, or a plurality of similar extending portions of a ferrous metal body; to provide apparatus for hardening a cam or plurality of cams on a camshaft in which sources of high temperature heat and quenching means are utilized, and in which the surfaces to be hardened are heated and quenched uniformly; to provide apparatus for hardening a plurality of cams upon a camshaft which is

easily adjustable to permit treatment of camshafts of varying lengths and cams of different widths; to provide such apparatus which will produce a relative reciprocal motion between the cams and a plurality of sources of high temperature heat directed onto the respective cams, and also between the cams and a plurality of quenching means; to provide such apparatus in which high temperature heating flames are directed from blowpipe heads against the portions to be hardened, and in which the blowpipe heads may be moved away from the body and simultaneously therewith the supply of gases to the blowpipe heads automatically turned off and a quenching medium to cool the heated surfaces automatically turned on; and generally to provide an apparatus whereby uniformly heat treated wearing surfaces can be consistently and economically duplicated. Other objects and novel features of this invention will become apparent from the following description and accompanying drawings, in which:

Fig. 1 is a front elevation of apparatus constructed in accordance with this invention and utilized in hardening simultaneously a plurality of cams upon a camshaft;

Fig. 2 is a bottom view, looking upwardly, of the apparatus of Fig. 1;

Fig. 3 is a vertical sectional view, taken along line 3—3 of Fig. 2, of the apparatus of Figs. 1 and 2;

Fig. 4 is a top view, looking downwardly, of the apparatus of Fig. 1, certain elements being omitted for the sake of clarity;

Fig. 5 is an enlarged partial horizontal view, illustrating the treatment of a cam by a heating blowpipe and quenching means;

Fig. 6 is a vertical view of the blowpipe, quenching means, and cam of Fig. 5;

Fig. 7 is a front elevation of apparatus constructed in accordance with this invention and forming a second embodiment thereof;

Fig. 8 is a top view, looking downwardly, of the central portion of the apparatus of Fig. 7, certain parts being omitted for the sake of clarity;

Fig. 9 is a vertical sectional view taken along line 9—9 of Fig. 7; and

Fig. 10 is a front elevation of a lathe illustrating the utility thereof in constructing apparatus such as that of Fig. 7.

Since cams generally are adapted to lift or actuate cam-follower, and each cam upon a camshaft usually actuates its follower only once during every rotation of the camshaft, the greater

or normal part of the cam surface is cylindrical in cross-section and an extending portion, usually substantially triangular in cross-section, is positioned at the point at which it is desired to lift or actuate the follower. Since the greatest wear will occur upon this extending portion, hereinafter termed the "apex," it is usually necessary to harden only the surface of the apex. Of course, when desired, the entire contacting surface of the cam may be hardened.

In accordance with this invention, apparatus for simultaneously hardening the apexes of a plurality of cams on a camshaft is constructed as in Figs. 1-4 in which the camshaft is mounted in a vertical position, or is constructed as in Figs. 7-9 in which the cam shaft is mounted in a horizontal position. In either instance, the camshaft is reciprocated longitudinally while heating flames are directed from suitable blowpipe heads against the surface portions to be hardened, and a cooling and quenching medium is then applied to the heated surfaces in order to harden the same. Each apparatus is provided with an operating handle or lever and so constructed that the blowpipe heads may be moved away from the heated surface portions, and, simultaneously therewith, the heating gases automatically turned off and the quenching fluid automatically turned on.

The apparatus illustrated in Figs. 1-4, in which the camshaft is mounted in a vertical position, comprises in general a plurality of specially constructed blowpipes B and quenching means Q for directing high temperature heating flames and cooling jets against cams A of a camshaft C, the cams having apexes spaced approximately 90° apart around the periphery of the camshaft. The blowpipes B and quenching means Q are supported by tubular stanchions 11, which at the lower ends thereof are mounted on carriers, such as slides S, in turn supported upon a platform P. The camshaft C is mounted in a vertical position between a center 12 of an upper supporting assembly U and a center 13 of a lower supporting assembly L, the points of centers 12 and 13 being inserted in the centering holes in the ends of camshaft C. The upper assembly U is supported by a vertical column 14 resting upon and preferably welded to platform P, and the lower assembly L is supported upon platform P but slidable therethrough.

Each blowpipe B directs heating flames over only a part of the width of the apex of each cam in order to accommodate the narrowest width of cam which may be treated. In order that the entire width of each apex will be heated, and also to produce a more uniform heating effect, the lower assembly L and camshaft C are reciprocated vertically by a motor M through suitable linkage, and with an amplitude sufficient to cause the heating flames to impinge upon substantially the entire width of each apex. The lower assembly L may be lowered to permit the replacement of a treated camshaft by an untreated one, or the placement of an untreated camshaft between centers 12 and 13; and further to facilitate the loading operation, the blowpipes B and quenching means Q may be withdrawn from their positions adjacent the camshaft by movement of stanchions 11 radially outwardly through movement of slides S, the latter movement being effected through a handle or lever H. The specific manner in which the above may be accomplished, as well as the manner in which the heating gases are automatically turned

off, and the quenching fluid automatically turned on, will be apparent from a later more detailed description.

5 The apparatus illustrated in Figs. 7-9, in which the camshaft is mounted in a horizontal position, comprises in general a plurality of blowpipes B, similar to the blowpipes of the apparatus of Figs. 1-4, and quenching means Q', which respectively direct high temperature heating flames and a quenching bath against cams A' of a camshaft C', the cams having apexes variably spaced around the periphery of the camshaft. The blowpipes B are supported by vertical quadrants 15, which are mounted on longitudinal plates 16; while longitudinal plates 15 are mounted on transverse slides S', in turn centrally mounted on a framework F which is similar to that of a lathe. The camshaft C' is held in its horizontal position between a right hand center 12' of a supporting assembly R and a left hand center 13', the points of centers 12' and 13' being inserted in the center holes in the ends of camshaft C'. The supporting assembly R is mounted on a horizontally adjustable support 17, similar to the tail-stock of a lathe, and center 13' is mounted in and horizontally reciprocable through an upright bracket portion 18 of framework F.

10 As before, each blowpipe B directs heating 30 flames over only a part of the width of the apex of each cam, and in this instance center 13' and camshaft C' are reciprocated horizontally by a motor M' through a suitable cam and linkage. The center 12' may be retracted to permit the replacement of a treated camshaft by an untreated one, or the placement of an untreated camshaft between the centers; and further to facilitate the loading operation, the blowpipes B are withdrawn from their positions adjacent the camshaft by movement of slides S' and plates 16 transversely outwardly, the movement being effected through a handle or lever H'. The specific manner in which the above may be accomplished, as well as other operational features, 20 will be apparent from a later more detailed description.

15 Referring now to Figs. 1-4, in the apparatus of which the camshaft is held in a vertical position, the operation of the apparatus therein illustrated and the novel features thereof will become apparent from the more detailed description which follows.

20 The upper assembly U, as in Fig. 1, includes the center 12; an externally threaded housing 20 having an adjusting wheel 21 and a cap 22 attached thereto; and a spring 23 bearing at its upper end against cap 22 and at its lower end against a circumferentially extending boss 24 of center 12. The spring 23 permits center 12 to 25 follow reciprocations of the camshaft, and also permits the camshaft to expand or contract during treatment. During reciprocation, center 12 oscillates within housing 20 and is guided at its upper end by cap 22 and at its lower end by boss 24 within the housing. A skirt 25, attached to the lower end of housing 20, extends downwardly over the upper end of camshaft C so as to prevent injury to the blowpipes and quenching means should the camshaft become dislodged from center 12 during reciprocation. A bracket 26 has an internally threaded portion at one end adapted to receive housing 20, and a split portion at the other end to permit the bracket to be adjustably clamped on column 14 by a clamping screw 27. Vertical adjustment of upper as-

sembly U to accommodate camshafts of different lengths may be obtained by raising or lowering bracket 26 upon column 14, and adjustment of the tension of spring 23 may be obtained through turning adjusting wheel 21.

The lower assembly L, as in Fig. 1, includes the center 13; a skirt 29, extending upwardly beyond the lower end of the camshaft for the same purpose as skirt 25 of the upper assembly; an indexing stud 30 secured in skirt 25 and inserted within the indexing hole of the camshaft to position the camshaft accurately in the apparatus and radially with respect to the blowpipes B and quenching means Q; and a skirt supporting sleeve 31 having an internally extending portion in threaded engagement with center 13 and also a depending skirt 32. The internally extending portion of the supporting sleeve is screwed tightly against a shoulder 33 formed on center 13, and depending skirt 32 prevents entry of quenching fluid into a lubricated guiding bearing or sleeve 34, within which center 13 reciprocates. Bearing 34, as in Fig. 3, is internally machined to fit center 13 and has an outwardly extending flange 35 resting upon, and secured to platform P by suitable means, such as bolts 36; and platform P is provided with a suitable aperture 37 through which the lower portion of bearing 34 extends.

The motor M, as in Fig. 3, is secured to the lower side of a mounting bracket 38, which is secured to the underside of platform P, preferably by welding; and the motor is also provided with a speed reducer 39, formed integrally therewith. A crank 40 provided with an adjustable block 41 is mounted upon a low speed shaft 42 of speed reducer 39, while a connecting rod 43 is pivotally attached at one end to the adjustable crank and at the other end, by a pin 44, to a link 45. The link 45 at one end is pivotally attached to the lower end of center 13 by a pin 46, and at the other end is pivotally attached to the upper end of a link 47 by means of a pin 48. The link 47 at its lower end is pivoted upon a normally fixed pin 49 so that when shaft 42 is rotated by motor M through speed reducer 39, the lower end of connecting rod 43 will revolve therewith, and a reciprocatory motion will be transmitted to center 13 through link 45.

The normally fixed pin 49, as in Figs. 2 and 3, connects link 47 with an arm 50, which is attached to a shaft 51 pivoted in collars 52, which are in turn mounted upon legs 53 of platform P. The pin 49 is held in its normally fixed position by an arm 54, secured at one end to shaft 51 and having at its other end a loading pedal 55. The loading pedal 55 is provided with an extension 56, normally held in the "down" position by a latch 57, which is attached to the lower end of a triangular supporting frame 58, as in Figs. 1 and 2. In order to place a camshaft within the apparatus for treatment, or to replace a treated camshaft with an untreated one, latch 57 may be released; and due to the weight of the lower assembly L, or that weight augmented by the weight of a treated camshaft and the pressure of spring 23, pedal 55 will rise to the dotted position of Fig. 1. The link 47, arm 54, and loading pedal 55 will then have assumed the dotted positions of Fig. 1; link 45 will have pivoted about pin 44 to assume its dotted position; and the entire assembly L will have been lowered, the center 13 also assuming its dotted position. A treated camshaft may then be removed and/or an untreated camshaft placed upon center 13.

with indexing stud 30 properly inserted within the indexing hole; and the newly inserted camshaft may subsequently be raised into contact with upper center 12 and, in position for treatment by depressing and latching pedal 55.

After a camshaft has been placed in position for treatment in the foregoing manner, motor M is started by means of a suitable control switch, which may be mounted in any convenient position, such as on leg 53 adjacent handle H. The amount of reciprocation is then tested, and block 41 adjusted to provide the amplitude necessary for the width of cam under treatment. When a plurality of camshafts having similar cams are being treated, only a single setting, that for the first camshaft, will be necessary.

A combustion supporting gas, such as oxygen, and a combustible gas, such as acetylene, are supplied to blowpipes B by hoses 60 and 61, respectively connected with vertical manifolds 62 and 63, as in Figs. 1 and 4. A cooling fluid, such as water, is supplied to blowpipes B by hoses 64, leading from a vertical conduit 65, and the warmed cooling water is led by hoses 66 from the blowpipes to a vertical discharge conduit 67. A quenching fluid, such as water, is supplied to quenching means Q by hoses 68, leading from vertical conduits 69. The vertical manifolds and conduits at their upper ends are plugged, and at their lower ends are provided with caps 70, secured to the sides of platform P in a suitable manner, such as by welding. The vertical manifolds and conduits are also attached to braces 71 by suitable means, such as clamps 72, to render them more firm. In order that the apparatus may be more efficiently operated, manifolds 62 and 63 and conduits 65 and 69, respectively, are provided with oxygen pressure gauges 73, acetylene pressure gauges 74, cooling water pressure gauges 75, and quenching water pressure gauges 76, disposed in vertically staggered relation, as in Fig. 1, to provide a better view of the same.

Oxygen and acetylene are supplied from mains 77 to manifolds 62 and 63. For this purpose, hoses 78 connect mains 77 and control valves V, which are attached to brackets 79 secured to either side of platform P, as in Fig. 2; while hoses 80 lead from valves V to caps 70 at the lower ends of the manifolds, as in Fig. 1. A common lever 81 is connected to handles 82 of the valves (shown in the "on" position in each of the figures), so that the gas supply to all of the blowpipes may be simultaneously shut off or turned on. Valves V are preferably of a type which will shut off the oxygen before the acetylene, to prevent pure oxygen from attacking the heated surfaces; and are also preferably of a snap-action type, i. e., when in the "on" position as shown, and handles 82 are moved slightly past a central position, the handles will snap to the "off" position.

Hoses 83, as in Fig. 1, lead from a water main 84 to conduits 65, which supply cooling water to blowpipes B; and suitable means (not shown) connects a branch water main 85 with conduits 69, which supply quenching water to quenching means Q. The branch main 85, as in Fig. 2, is provided with a shut-off valve 86 and a plunger operated valve 87, the latter being actuated by a cam 88 having a configuration similar to that illustrated. The cam 88 is pivoted at one end on a pin 89 secured to the underside of platform P, and at the other end is slidably within and supported by an elongated bracket 90, which is also secured to the underside of platform P.

The slides S, as in Fig. 4, include ways 91 and slideable plates 92. Ways 91 are attached to platform P by suitable means, such as bolts 93, and ways 91 and plates 92 form rectangular tongue and groove connections. Two opposite stanchions 11 are attached directly to plates 92 by suitable means, such as by welding; while the other two stanchions are attached in the same manner to plates 94, which pivot upon studs 95 secured to plates 92, as in Fig. 3. Nuts 96 permit plates 94 to be clamped in any angular relation to plates 92, and permit these two stanchions and plates 94 to be swung to the dotted positions of Fig. 4, so that camshafts having cam apices disposed substantially 120° apart may be treated by using only three sets of blowpipes and quenching means.

In order to move sliding plates 92 toward and away from the camshaft, plates 92 are provided with studs 97, as in Fig. 3, which extend downwardly through slots 98 in platform P. Studs 97 are pivotally attached to links 99, and links 99 are in turn pivotally attached to the four corners of a square plate 100 having a relatively large circular aperture machined in the center thereof. A plurality of rollers 101, secured to the underside of platform P, are provided with grooves slightly wider than the thickness of plate 100 so that the plate will be supported by the rollers and rotate within the grooves; and plate 100 may be formed integrally with handle H, as in Fig. 2.

Oxygen and acetylene may be turned on by moving a handle 102 of a rod 103. As in Fig. 2, rod 103 is pivoted in suitable apertures in legs 104 of platform P, and is provided with a pin 105 extending into a hole 106 in lever 81. By turning handle 102, lever 81 may be moved to a desired position, such as that shown in Fig. 1, in which the handle has been turned in the direction of the arrow to turn on the oxygen and the acetylene.

Handle H is movable along the upper leg of triangular supporting frame 58, as in Figs. 1 and 2. In the extreme left hand or operating position, handle H is adjacent a bracket 107 which, with a bracket 108, supports triangular frame 58. The upper leg of triangular frame 58 is provided with an interference 109, so placed that as soon as the cam apices under treatment have been heated sufficiently, handle H may be shifted from left to right until it contacts the interference, or into quenching position. During this movement, handle H will cause the blowpipes to be partially retracted, the heating gases to be turned off, and the quenching water to be turned on. A pin 110, as in Fig. 2, depending from plate 100, contacts an adjustable stop 111 attached to valve lever 81 in order to turn off the supply of gases to the blowpipes. The distance handle H moves before contacting interference 109 is so proportioned to cause handles 82 of valves V to be moved just past their central position, the handles then snapping to the "off" position in the manner previously described. At the same time, a hinged clevis 112, attached to plate 100 and provided with a roller 113 operating against cam 88, turns on the quenching water by causing the plunger of valve 87 to be depressed. In case valves of other than the snap-action type are utilized, stop 111 may be slidably mounted upon lever 81 and connected thereto by a spring having a suitable resistance to movement of stop 111. Such a spring will cause the valves to be closed during movement of handle H from its left hand posi-

tion to interference 109, but will permit stop 111 to slide along lever 81 when handle H is moved to the extreme right hand position.

As soon as the heated cam apices have been cooled sufficiently to harden the same, handle H is moved over interference 109 to its extreme right hand position adjacent bracket 108. Slides S will then be moved to their extreme outward position and the quenching water will be turned off, since due to the configuration of cam 88 roller 113 will no longer depress the cam sufficiently to keep valve 87 open. As soon as the slides are in their extreme outward position, the treated camshaft may be removed and an untreated one positioned in the apparatus in the manner previously described. After the untreated camshaft has been placed in position, handle H is moved from right to left to move the slides inwardly, thereby placing blowpipes B in heating position. To prevent the quenching water from being turned on when handle H is moved from right to left, hinged clevis 112 is provided with a spring 114 which normally holds the clevis in extended position, but permits the clevis to pivot so that roller 113 will pass lightly over cam 88.

A lighting blowpipe (not shown) may be provided which may hang upon a suitable bracket, such as a hook 115 attached to the side of platform P, as in Figs. 1 and 4; or the lighting blowpipe may be a separate piece of apparatus utilized in conjunction with the apparatus herein disclosed. This lighting blowpipe is preferably an air-acetylene or air-city-gas torch which is passed quickly over the full length of the camshaft at the same time that control valves V are turned on, so that all of blowpipes B will be lighted substantially simultaneously.

Each blowpipe B, as in Fig. 1, includes a body 117 provided with suitable control valves to control the flow of oxygen and acetylene from hoses 60 and 61 to a suitable mixer disposed within body 117. The blowpipes are secured to stanchions 11 by adjustable clamps 118, which permit the blowpipes to be positioned in any vertical position on the stanchions, and also in any horizontal angular relation to the stanchions. Attached to the forward end of body 117 is a tube 119 for conveying the combustible mixture to a fork 120, as shown more clearly in Figs. 5 and 6. Heads 121 and 122, right and left hand (looking from above), are attached to the double end of fork 120. Heads 121 and 122 are provided with suitable passages and outlets for the combustible mixture, which is directed as flames 123 upon only a portion longitudinally of the apex of cam A; and each blowpipe B is so positioned that the faces of heads 121 and 122 are substantially parallel to the sides of the apex.

The heating flames may be directed from a plurality of orifices, disposed in several rows in the faces of the heads, or from two or more slots. The heating flames are also directed upon only a portion laterally of the apex, so that the point of the apex will receive heat chiefly, or from a practical standpoint only, by conduction. Also, the amplitude of reciprocation is preferably such that the flames are not applied directly to upper and lower edges 124 and 125, respectively, of the apex, as will appear later. This results in a more uniform heating of the entire surface to be hardened, since the tendency for a lesser amount of heat to be conducted away from the point and also the edges of the apex is compensated for.

The head 122 is provided with an inlet connec-

tion 126, to which cooling water hose 64 is attached; and the heads are also provided with suitable passages so that cooling water is passed through head 122, entering at the top, through a cross-over connection 127 to the bottom of head 121, and discharged at the top of head 121, through an outlet connection 128 to cooling water outlet hose 66. It will be obvious that the arrangement of the elements for passing cooling water through heads 121 and 122 may be varied considerably.

The quenching means Q includes a jet directing head 130 disposed between heads 121 and 122 and supported by a clamp 131 attached to tube 119 of the blowpipe; and head 130 is provided with an inlet connection 132, to which quenching water hose 68 is attached.

The camshaft is reciprocated longitudinally from the full upper position to the dotted lower position of Fig. 6. In the upper position of the camshaft, lower edge 125 of the apex approximately coincides with the lower edges of heads 121 and 122, so that the flames will not be applied directly to lower edge 125; and in the lower dotted position, upper edge 124 of the apex approximately coincides with the upper edge of the heads 121 and 122, so that the flames will not be applied directly to the upper edge of the apex. When the surface of the apex has reached the proper temperature, handle H may be moved to the quenching position, i. e., into engagement with interference 109, where, as previously explained, the oxygen and acetylene is automatically turned off and the quenching water automatically turned on. At the same time heads 121 and 122 and jet-directing head 130 will assume the dotted positions of Fig. 5, in which the quenching water is directed from head 130 onto the point of the apex to spread in two streams along each inclined side of the surface of the apex.

In treating camshafts having cams whose apexes are spaced approximately 120° apart, i. e., when the movable stanchions 11 are disposed in the dotted positions of Fig. 4, it is desirable to position the jet directing heads mounted on these movable stanchions at the sides of the respective blow-pipe heads. This compensates for the shift sidewise when these stanchions are moved to the quenching position, since the jet directing heads would otherwise no longer be directly in line with the points of the apexes. When the jet directing heads are so positioned, the quenching medium will be directed upon the point of each apex and flow evenly along each side thereof.

Referring now to Figs. 7-9, in the apparatus of which the camshaft is held in a horizontal position, a more detailed description of this second embodiment follows.

The right hand supporting assembly R, which is similar to the upper assembly U of Fig. 1, comprises center 12'; an externally threaded housing 20' having an adjusting wheel 21' and a cap 22' attached thereto; and a spring 23' bearing at one end against cap 22' and at the other end against a circumferentially extending boss 24' of center 12'. As before, a skirt 25' is attached to the end of the supporting assembly to prevent injury to the blowpipes should the camshaft become dislodged; support 17 has an internally threaded portion adapted to receive housing 20'; and a clamping screw 27' permits the position of support 17 to be adjusted to accommodate camshafts of different lengths. As

will be apparent, each of the parts just described serves the same purpose as corresponding or similar parts of the apparatus of Fig. 1. However, since handwheel 21' is in a relatively accessible position, this handwheel may be used in moving center 12' away from the end of a treated cam-shaft which is being removed, or in moving center 12' toward an untreated camshaft which is being placed in position for treatment.

10 A head 135, provided with an indexing stud for insertion in the indexing hole of camshaft C', is threaded or otherwise suitably secured to center 13'. A skirt and skirt-supporting sleeve, as in the first embodiment, may also be secured to head 135.

15 The motor M' is secured to a mounting bracket 38' attached to framework F, and is provided with a speed reducer 39', formed integrally therewith. To reciprocate center 13', a cam 136

20 is mounted upon the low speed shaft of speed reducer 39', while a link 45' is provided at one end with a roller or cam-follower 137. A pin 46' attaches link 45' to center 13', and link 45' oscillates about a fixed pin 48', which is secured in a U-shaped support 138 attached to bracket

25 18. Cam 136 may be replaced by other suitable cams for treating camshafts having cams of different widths, but an adjustable crank, as in the first embodiment, may be substituted for cam 136 and follower 137. A suitable switch for 30 starting and stopping motor M' may be mounted in any convenient position, such as on framework F adjacent handle H'.

Quadrants 15 are mounted on plates 16 in any 35 suitable manner, such as by clamping bolts 139 which extend through longitudinal slots in plates 16, so that each quadrant may be adjusted longitudinally of plate 16 to cause the position of each blowpipe B to coincide with the particular cam to be treated.

40 The blowpipes B of the second embodiment are similar in construction to those of the first embodiment, but are not provided with attached jet directing heads. Tubes 119 of the blowpipes, as 45 in Fig. 9, are adjustably secured to quadrants 15 by U-clamps 140. Tubes 119 pass through suitable apertures in each leg of clamps 140, and are held against one side of the quadrants by wing screws 141 which are threaded through clamps 140, the wing screws bearing against the opposite 50 sides of the quadrants. By loosening wing screws 141, blowpipes B may be slipped toward or away from camshaft C' for positioning purposes, and clamps 140 may be moved along quadrants 15 to align each heating head radially with respect to 55 the particular cam apex to be heated. Wing screws 141 may then be tightened against quadrants 15, and the blowpipes and heating heads thereby secured in operative heating position.

60 Blowpipes B are supplied with oxygen and acetylene by hoses 60' and 61', respectively. Hoses 60' and 61' are respectively connected with pipes or manifolds 62' and 63', the manifolds being disposed horizontally along both the front and rear of framework F. The flow of gases to the manifolds and blowpipes is controlled by a valve V', mounted at the rear of the framework, as in Fig. 8. Inlet hoses 18' connect valve V' with suitable sources of supply of a combustible gas, such as acetylene, and a combustion supporting gas, such as oxygen; while hoses 80' lead from valve V' to the front manifolds, and hoses 80'' to the rear manifolds.

65 Valves V' are preferably of a push-to-open type, buttons 142 thereof being spring-loaded so

that when pushed inwardly by pressure of a block 143, the heating gases will be turned on. Conversely, when the pressure exerted by block 143 is removed, the heating gases will be shut off. Buttons 142 are preferably adjustable in length, or differ in length, so that the oxygen will be shut off before the acetylené, for reasons previously set forth.

As previously indicated, handle H' is utilized in moving slides S' and plates 16 transversely outwardly to cause blowpipes B to be withdrawn from the heating position. For this purpose, handle H is secured to, or made integrally with, a disc 144, while links 145 and 146 pivotally connect disc 144 with front and rear slides S', respectively. Disc 144 pivots about a pin 147 secured to a supporting bracket 148, and bracket 148 is in turn secured to the front of the bed of framework F in a suitable manner, such as by welding.

When handle H is disposed alongside framework F, as in the full position of Fig. 8, slides S' will be disposed closely together with blowpipes B in heating position; and when handle H is moved outwardly through an arc of 90°, such as to the dotted position in Fig. 8, links 145 and 146 will cause slides S' to move outwardly away from each other to the loading, or dotted, position of Fig. 8. When in the loading position, a treated camshaft may be removed, and/or a camshaft to be treated may be placed between centers 12' and 13', center 12 being moved toward or away from the camshaft by handwheel 21' as previously described.

After the camshaft to be treated has been placed in position, motor M' is started to reciprocate the camshaft and handle H is swung to the heating position, the heating gases being automatically turned on by pressure of block 143 against buttons 142 of valve V'. Block 143 is secured to the lower end of an angle bracket 149 by a bolt 150, angle bracket 149 being bolted or otherwise suitably secured to the rear slide. Block 143 may be turned to the dotted position of Fig. 8, so that the heating gases will not be turned on even though handle H is in the heating position, thereby permitting alignment and adjustment of the blowpipes with respect to the cams to be treated. In treating a plurality of identical camshafts, such alignment and adjustment is necessary only in the case of the initial camshaft treated.

When the blowpipes have been moved into heating position, and the heating gases turned on, the heating flames may be ignited by a suitable lighting blowpipe passed quickly along the length of the camshaft. The lighting blowpipe, as in the first embodiment, may be an air-fuel gas, or air-city gas torch.

As soon as the cam apices reach the desired temperature, usually after a timed interval of heating the extent of which is determined previously by experiment or otherwise, handle H' is moved away from the framework to the quenching position, which corresponds to the position of handle H when it contacts interference 109 of Fig. 2. As handle H' is moved outwardly, the pressure of block 143 against buttons 142 of valve V' will be removed, the heating gases thereby being turned off; and a cam 152 will turn on valve 87', which controls the flow of quenching fluid through a hose 153 to the quenching means Q'. Quenching fluid under suitable pressure is supplied to valve 87' by a pipe 154, provided with a shut-off valve 155.

The quenching means Q' comprises a header or pipe 157 from which lead a plurality of branch pipes 158. Header 157 is disposed at the rear and above the remainder of the apparatus, and branch pipes 158 extend forwardly to a point above the camshaft and then downwardly towards the same. Branch pipes 158 are preferably screwed into threaded outlets in header 157, so that each branch pipe may be positioned at various longitudinal points which correspond with the positions of the cams on different types of camshafts. In addition, the threaded outlets in header 157 are sufficiently numerous to permit the connection of branch pipes for treating a camshaft having a greater number of cams, unused threaded outlets being closed by suitable means, such as plugs 159.

The header and branch pipes are sufficiently large to direct a bath of cooling medium onto the heated surfaces, bed 160 of framework F forming a trough which collects the used cooling medium. The cooling medium may be water, or a special quenching solution, such as an aqueous solution of sodium hydroxide. In the former instance, the water may be led from the collecting trough to a waste drain in any suitable manner; and in the latter instance, the quenching solution may be returned by suitable means, such as a pump (not shown) to a tank located above the apparatus.

After the heated surfaces are cooled sufficiently to harden the same, handle H' is moved to the dotted position of Fig. 8, the loading and unloading position. During this movement, the quenching medium will be turned off in the following manner. Cam 152 is pivoted at one end on a lower horizontal arm of an angle bracket 162, the upper vertical arm of which is bolted or otherwise suitably secured to the rear slide. The other end of cam 152 is beveled to engage a roller 163 mounted on one end of an operating handle or lever 164 of valve 87'. Cam 152 is so positioned with respect to roller 163 that when in the quenching position valve 87' will be opened; but when handle H' is moved to the loading and unloading position, after the heated cam apices have been quenched and thereby hardened, cam 152 will slip past the roller 163 and valve 87' will close.

After the treated camshaft has been removed and a camshaft to be treated has been placed in position for treatment, handle H' is moved again to the heating position. During this movement, cam 152 will pivot on roller 163, assuming the dotted position of Fig. 8 as the front and rear slides move toward each other, and cam 152 will thereafter slip past roller 163. A spring 165 pulls cam 152 back to its extended position against a stop 166 after the cam has slipped past roller 163, and cam 152 will then be in operative position for the next quenching operation.

When a tank of quenching liquid located above the apparatus is utilized, valve 87' may be located just beneath the tank, or at any suitable position in a line between the tank and header 157. In such a case, an extension rod may connect lever 164 and a lever similar thereto for operating valve 87' in its new position, but other suitable ways in which the quenching medium may be turned on may be utilized.

The second embodiment, which has just been described, is particularly useful in hardening a plurality of identical camshafts; and, in addition, an old lathe bed may be utilized as a supporting framework. As will be apparent from

Fig. 10, no substantial alteration is made in the lathe to adapt it for such use, except that front and rear slides are substituted for the usual single cross slide, the tool carriage of the lathe remaining clamped in a central position. The tail-stock center 12" is spring-loaded in the same manner as center 12' of Fig. 7, and the head-stock of the lathe is utilized as a bearing and support for reciprocating center 13'. Other attendant parts, for reciprocating the camshaft, such as motor M', cam 136, and link 45' are substantial duplicates of similar parts of Fig. 7. Plates 16, and attendant parts for supporting the blowpipes are mounted on slides S'. Handle H' and cooperating parts for moving slides S' toward and away from each other, and for automatically turning on and off the heating gases and quenching medium, are preferably substantial duplicates of corresponding parts of the apparatus of Figs. 7-9.

The operation of the apparatus in which a lathe is utilized as the framework is identical with the operation of the apparatus of Figs. 7-9.

In each of the embodiments described, the camshaft is reciprocated longitudinally during both heating and quenching, and the quenching medium is applied to the heated surfaces substantially simultaneously with the discontinuance of heating. In addition, by resiliently supporting the camshaft at one end, thereby permitting longitudinal expansion or contraction during treatment, warping or distortion is prevented. These factors produce more uniform results, both in the case of the individual cams in a single camshaft, and in the case of each of a plurality of similar camshafts. Thus, the uniform results secured in treating a single camshaft can be duplicated with success for any number of camshafts. Obviously, such successful duplication of results is of particular importance in large scale commercial operations.

While the apexes of the cams illustrated have sides of the same length, it may be desirable to treat apexes having sides of unequal length, or one or both sides of a curved or other special contour to provide a particular sort of motion to a follower. In such instances, heads 121 and 122 may be replaced by other heads having a plurality of nozzles or orifices adapted to produce a flame pattern in accordance with the length or the contour of such surfaces, or a reciprocatory motion other than simple harmonic may be imparted to centers 13 or 13' by substituting a suitable cam and follower for crank 40 of Figs. 1-3 or a different cam for cam 136 of Fig. 7, in order to harden uniformly the surfaces of apexes of unusual shape. In addition, it may be desirable to substitute for fork 120 an adjustable connection so that heads 121 and 122 may be moved closer together or further apart to accommodate cams having apexes of dimensions different from those illustrated.

While the hardening of the surface of the apexes of cams has been illustrated, it may be desirable in some instances to harden a greater portion of the cams, and for that purpose heads 121 and 122 may more nearly encircle the cams so as to heat a greater portion of the surface of the cams. In addition, the principles of this invention may be applied to metal bodies other than camshafts which have a plurality of similar projections or laterally extending portions to be hardened, or a plurality of portions of the same longitudinal extent to be hardened. Other

changes may be made without departing from the scope of this invention.

What is claimed is:

1. Apparatus for heat treating a plurality of cams upon a camshaft, comprising a plurality of blowpipes for applying high temperature heat to said cams; means for supporting said camshaft in operative relation with respect to said blowpipes, said means including two members adapted to engage said camshaft at either end thereof; means for reciprocating said camshaft and said members longitudinally of said camshaft; and means disposed closely adjacent to and surrounding the ends of said camshaft for preventing damage to said blowpipes in case said camshaft becomes dislodged from either of said supporting members during reciprocation.
2. Apparatus for heat treating a plurality of cams upon a camshaft, comprising means for applying high temperature heat to said cams; means, including reciprocable members in contact with said camshaft at the ends thereof, for supporting said camshaft in operative relation with respect to said heating means; means for reciprocating said members and said camshaft, said reciprocating means including linkage means reciprocable about a normally fixed center; and means connected with said linkage means at said normally fixed center for moving said normally fixed center and thereby move one of said contacting members toward or away from the other of said contacting members.
3. Apparatus for heat treating a plurality of cams upon a camshaft, comprising a plurality of blowpipes for applying high temperature heat to said cams; means for supplying a combustible gas and a combustion supporting gas to said blowpipes; means for supporting said camshaft; means for applying a quenching fluid to said cams; means for supporting said blowpipes in operative relation with respect to said camshaft; means for supplying said quenching means with a quenching fluid; means for moving said blowpipe supporting means toward and away from said camshaft so as to move said blowpipes toward and away from said camshaft; and means operatively connected with said moving means for turning off the supply of gases to said blowpipes and turning on the supply of quenching fluid to said quenching means when said supporting means is moved away from said camshaft.
4. Apparatus for heat treating a plurality of cams upon a camshaft, comprising a platform; means for supporting said camshaft perpendicularly with respect to said platform; a plurality of carriers upon said platform and disposed radially about said camshaft and movable toward and away from said camshaft; a plurality of supports attached to said carriers and movable therewith toward and away from said camshaft; a plurality of blowpipes and quenching means mounted upon said supports and adjustable vertically thereupon; and means for moving said carriers toward and away from said camshaft.
5. Apparatus as defined in claim 4, in which at least one of said blowpipe supports is adjustably pivoted upon one of said carriers.
6. In apparatus for heat treating a plurality of cams upon a camshaft, the combination comprising means for supporting said camshaft at either end thereof; a plurality of blowpipes for directing high temperature heating flames against the surface of each of said cams; a pair of carriers for moving said blowpipes toward and away from said cams; a plurality of curved mem-

bers attached to said carriers and movable therewith, said members being curved in a direction substantially perpendicular to the longitudinal axis of said camshaft; and adjustable means for securing said blowpipes to said curved members whereby the position of each of said blowpipes may be adjusted radially about said camshaft.

7. Apparatus for heat treating a plurality of cams upon a camshaft, comprising reciprocating means engaging one end of said camshaft to reciprocate said camshaft in the direction of its longitudinal axis; a relatively stationary support disposed adjacent the opposite end of said camshaft; supporting and aligning means engaging the opposite end of said camshaft and mounted on said support so as to be reciprocable relative to said support in the direction of the longitudinal axis of said camshaft; resilient means operatively connecting said support and said supporting and aligning means for urging the latter toward said reciprocating means; and means for applying high temperature heat to said cams.

8. Apparatus for heat treating a plurality of cams upon a camshaft as claimed in claim 7, including means for adjusting the force exerted by said resilient means upon said supporting and aligning means.

9. Apparatus for heat treating a plurality of cams upon a camshaft, comprising a plurality of

blowpipes for applying high temperature heat to said cams; means for supplying a combustible gas and a combustion supporting gas to said blowpipes; means for supporting said camshaft; means for applying a quenching fluid to said cams; means for supporting said blowpipes in operative relation with respect to said camshaft; means for supplying said quenching means with a quenching fluid; means for moving said blowpipe supporting means toward and away from said camshaft so as to move said blowpipes toward and away from said camshaft; and means operatively connected with said moving means for turning off the supply of gases to said blowpipes and turning on the supply of quenching fluid to said quenching means when said supporting means is moved away from said camshaft to a predetermined position, and for turning off the supply of quenching fluid when said supporting means is moved away from said camshaft further than said predetermined position, said connected means being inoperative during subsequent movement of said blowpipe supporting means toward said camshaft so that the supply of quenching fluid to said quenching means will not be turned on during such subsequent movement.

HOMER W. JONES.
